UNITED STATES PATENT OFFICE.

THOMAS L. BURTON, OF ST. LOUIS, MISSOURI, ASSIGNOR TO THE AMERICAN BRAKE COMPANY, OF ST. LOUIS, MISSOURI, A CORPORATION OF MISSOURI.

BRAKE-HEAD CONNECTION.

1,199,871.

Specification of Letters Patent.

Patented Oct. 3, 1916.

Original application filed February 20, 1915, Serial No. 9,583. Divided and this application filed March 4, 1916. Serial No. 82,037.

To all whom it may concern:

Be it known that I, THOMAS L. BURTON, a citizen of the United States, residing at St. Louis, in the State of Missouri, have invented a certain new and useful Improvement 5 in Brake-Head Connections, of which improvement the following is a specification.

This invention relates to brake heads and hangers therefor, and has for its object to 10 provide improved connecting means whereby the brake head and shoe will be automatically adjusted upon its pivot, by engagement with the car wheel, to such position that the shoe is concentric with the 15 wheel, and then be retained in the same position relative to the hanger until again shifted by engagement with the wheel.

In the accompanying drawings: Figure 1 is a side elevation of a brake head and hanger 20 showing one form of connection embodying my improvement; Fig. 2, a transverse section of the same; Fig. 3, a side elevation showing another modification; Fig. 4, a transverse section of the same; and Figs. 25 5 to 12 inclusive, similar sections showing other modifications.

It is important in the operation of railway brakes that the brake heads be supported in such a manner that when the brakes 30 are released all parts of the rubbing surfaces of the shoes are effectually prevented from coming into contact with the wheels, otherwise undesirable wear and loss of power would be occasioned. At the same time it 35 is equally important that when the brakes are applied, the shoes be permitted to so adjust themselves relatively to the wheels that the rubbing surfaces of the shoes become concentric with the wheels, thus providing for substantially uniform pressure 40 and wear on all parts of the rubbing surfaces of the shoes.

According to the construction shown in Figs. 1 and 2 of the drawings, the brake head, 1, carrying the shoe, 2, is pivotally mounted on the hanger, 3, by means of a pin, 4, passing through the hanger and the two flanges of the brake head. According to my improvement, one of the supporting flanges 50 of the brake head is provided with an opening in which is mounted a longitudinally movable bushing, 5, on the connecting pin, 4, while a spring and clamping nut on the pin serve to exert a pressure and produce a

corresponding frictional resistance between 55 said bushing and the hanger, and between the hanger and one of the brake head flanges. As shown in Figs. 1 and 2, the movable bushing, 5, is of hexagonal or other non-circular form, and contains a recess 60 for the head of the pin or bolt, 4, so that the bushing and bolt turn with the brake head.

The hanger, 3, is provided with friction surfaces upon its opposite sides around the bolt opening for engaging a corresponding surface on the bushing on one side and on the other brake head flange on the other side, these parts being pressed against each other by the spring, 6, which is mounted on the 70 bolt outside of one of the brake head flanges and bears at its outer end against the washer, 7, held by the nut, 8, on the bolt. The force of the spring holds the friction faces in contact with sufficient pressure to maintain the same relative position between the 75 brake shoe and hanger when the brake is released as when applied to the wheel. In this way all parts of the rubbing surface of the shoe are effectually prevented from 80 coming into contact with the wheel when the brake is released, and at the same time the shoe is permitted to readily so adjust itself relatively to the wheel that the rubbing surface of the shoe becomes concentric with 85 the wheel when the brake is applied, for as soon as any wear of other cause tends to disturb this relation, the application of the shoe to the wheel will force the head to turn slightly on its pivot pin on the hanger 90 and sufficiently to reestablish the concentric relation above referred to. The frictional engagement between the surfaces of the brake head and the movable bushing and the corresponding surfaces on the hanger 95 will then hold the parts in this position until further adjustment is made.

According to the modification shown in Figs. 3 and 4, the longitudinally movable bushing, 5^a, is cylindrical, and is mounted in 100 the flange of the head on the same side as the spring. In this case, the bushing may turn with the hanger and relatively to the brake head unless the torsional resistance of the spring, 6, is exceeded, in which event 105 relative motion will occur between the bushing and the hanger, or between the bushing and the spring, or between the spring and

the washer, 7, or between the washer and the nut, 8, which is constrained to turn with the brake head. In any case there is the frictional resistance to the motion of the hanger relatively to the brake head of the engaging surfaces of the hanger and the brake head flange on the other side, which is ample for the purpose intended.

In the modification shown in Fig. 5, a short coil of square section spring, 5^b, serves both as the longitudinal movable bushing and as the spring, and bears directly upon the friction face at one side of the hanger, passing through the enlarged cylindrical opening in the flange of the brake head.

According to Fig. 6, the spring, 6, is dispensed with, and in lieu thereof, a spring washer, 9, is used under the head of the bolt, 4.

In Figs. 3 to 6 inclusive, it is apparent that the frictional engagement with the left side of the hanger is not a positive one, for if the head is rotated relatively to the hanger, the bushing, 5^a, or its equivalent, 5^b, will rotate with the hanger, coiling or uncoiling the spring about its central axis until the torsional resistance of the spring becomes sufficient to prevent its further distortion; then when the force which occasioned the rotation of the head ceases to be exerted on it, the tendency of the spring to recoil will continue to cause a force to act on the head tending to restore the head to its original position relative to the hanger.

In order to maintain the same relative position between the brake head and hanger when the brake is released as when applied, it is important that the frictional engagements on which the maintenance of this relation depends be positive in their action and free at all times from any tendency to cause rotation of the head relatively to the hanger.

In Fig. 7 it will be noted that the construction is similar to that of Figs. 3 and 4, with the exception that the bushing, 5^a, is prevented from rotating relatively to the brake head by means of the key, 10, and the bolt, 4, the head of which is lodged in a recess in one of the side flanges. In Fig. 8, the bushing, 5^a, is prevented from rotating relatively to the brake head by means of the key, 10^a, engaging with the left-hand side flange. It will be observed that in both of these figures means are provided for forming two positive frictional engagements with the surfaces of the hanger, each of which is adapted to uniformly oppose the rotation of the brake head relatively to the hanger.

The constructions shown in Figs. 9 and 10 are substantially the same as those of Figs. 1 and 2, with the exception that instead of the bushing, 5, the bolt itself is adapted to

form a bearing for the brake head flange and also to have frictional engagement with the face of the hanger. In Fig. 9 the bolt is provided with an enlargement or collar, 4^a, and in Fig. 10 the head of the bolt itself is extended to perform the functions in question. In both cases the bolt is prevented from rotating relatively to the brake head by means of a hexagonal recess in the side flange which engages the bolt head. 75

In Fig. 11, a bushing, 5^a, rotatable relatively to the brake head is mounted on the bolt, 4, within the left side flange. The bolt, 4, is non-rotatably connected with the hanger by means of the key, 12, and the head of the bolt is adapted to have frictional engagement with the outer surface of the right-hand side flange. The object of this construction is to provide positive frictional engagements with the inner and outer surfaces of one of the side flanges. 85

In Fig. 12, the bushing, 5, which is rotatable relatively to the brake head is mounted on the bolt, 4, within one of the side flanges, also a washer, 11, is mounted on the bolt, 4, outside of the other side flange and is prevented from rotating relatively to the bolt by means of the key, 10. A key, 12, connects the bolt, 4, with the hanger, 3, so that these parts cannot rotate relatively to each other. It is apparent that the spring, 6, presses the washer, 11, and the hanger, 3, into frictional engagement with the opposite faces of one of the side flanges, also that both of these engagements are of a positive character, for when the hanger is rotated relatively to the brake head, the bolt, 4, and washer, 11, must turn with it. It will be obvious that, if preferred, the bushing may be integral with the bolt. 95 100 105

This application is a division of my prior application Serial No. 9563, filed February 20, 1915.

Having now described my invention, what I claim as new and desire to secure by Letters Patent is:

1. The combination of a brake head having side flanges, a hanger between said flanges and rotatable relatively thereto, and means for forming frictional engagement with the surface of said hanger to oppose its rotation relatively to the brake head. 115

2. The combination of a brake head having side flanges, a hanger between said flanges and rotatable relatively thereto, and means for forming a plurality of frictional engagements with the surfaces of the side flanges to oppose the rotation of the brake head relatively to the hanger. 120

3. The combination of a brake head having side flanges, a hanger between said flanges, and means for causing a frictional engagement between the surface of said hanger and one of the side flanges. 125

4. The combination of a brake head hav-

- ing side flanges, a hanger between said flanges, a bolt passing through the same, a bushing mounted on said bolt within the opening in one of the side flanges, and means for pressing the bushing and one of said flanges into frictional engagement with the hanger. 5
5. The combination of a brake head having side flanges, a hanger between said flanges, a bolt passing through the same, a bushing mounted on said bolt within the opening in one of the side flanges, and a spring mounted on said bolt outside of said flanges for forcing the bushing and one 10 flange into frictional engagement with the hanger. 15
6. The combination of a brake head having side flanges, a hanger between said flanges, a bolt passing through the same, a bushing mounted on said bolt within the opening in one of said side flanges, and connected with the brake head, and a spring on said bolt for forcing the parts into frictional engagement with each other. 20
- 25 7. The combination of a brake head having side flanges, a hanger between said flanges, a bolt passing through the same, a longitudinally movable bushing mounted on said bolt within the opening of one of the side flanges, and means for pressing the bushing and one of said flanges into frictional engagement with the hanger. 30
8. The combination of a brake head having side flanges, a hanger between said flanges, a bolt passing through the same, a longitudinally movable bushing mounted on said bolt within the opening in one of the side flanges, and a spring mounted on said bolt outside of said flanges for forcing the 35 bushing and one flange into frictional engagement with the hanger. 40
9. The combination of a brake head having side flanges, a hanger between said flanges, a bolt passing through the same, a 45 slidable bushing mounted on said bolt within the opening in one of the side flanges, and connected with the brake head, and a spring on said bolt for forcing the parts into frictional engagement with each other. 50
10. The combination of a brake head having side flanges, a hanger between said flanges, a bolt passing through the same, a bushing mounted on said bolt within the opening in one of the side flanges, and connected with the brake head, a recess in said 55 bushing for the bolt head, and a spring on the other end of the bolt for forcing the bushing and one of the flanges into frictional engagement with the hanger. 60
11. The combination of a brake head having side flanges, a hanger between said flanges, a bolt passing through the same, a bushing mounted on said bolt within the opening in one of the side flanges, and connected with the brake head, and means for 65 forcing the bushing and one of the side flanges into frictional engagement with the hanger. 70
12. The combination of a brake head having side flanges, a hanger between said flanges, a bolt passing through the same, means adapted to form a bearing for one of the brake head flanges mounted on said bolt on one side of the hanger, and having engagement therewith, a non-rotatable member connected with the bolt on the opposite side of the hanger, and having frictional engagement with the other side flange, and means for preventing the bolt from rotating 75 relatively to the hanger. 80
13. The combination of a brake head having side flanges, a hanger between said flanges, a bolt passing through the same, means adapted to form a bearing for one of the brake head flanges mounted on said bolt 85 on one side of the hanger, and having engagement therewith, a non-rotatable member connected with the bolt on the opposite side of the hanger, means for preventing the bolt from rotating relatively to the hanger, 90 and means for forcing the hanger and said non-rotatable member connected with the bolt into frictional engagement with the brake head. 95

In testimony whereof I have hereunto set my hand.

THOMAS L. BURTON.
